[57] CLAIM

The ornamental design for a heavy duty vehicle brake shoe gauge, as shown and described.

DESCRIPTION

FIG. 1 is a top plan view of a heavy duty vehicle brake shoe gauge showing my new design; the bottom plan view being a mirror image of FIG. 1;
 FIG. 2 is a front elevational view thereof;
 FIG. 3 is a rear elevational view thereof;
 FIG. 4 is a left end elevational view thereof; and
 FIG. 5 is a right end elevational view thereof.
 The broken-line showing of FIG. 2 is environmental and forms no part of the claimed design.
